SIDE PORTED WELL CASING CEMENTING COLLAR

Francis Hampton Lee, San Pedro, Calif., assignor
to Baker Oil Tools, Inc., Vernon, Calif., a corporation of California

Application February 24, 1947, Serial No. 730,348

13 Claims. (Cl. 251—8)

1

The present invention relates to devices adapted to form part of a well casing, liner or similar conduit string, and having side ports selectively opened or closed to control lateral flow of fluids between the interior and exterior of the conduit string.

An object of the invention is to provide an improved telescopic side ported collar adapted to be incorporated in a casing or similar conduit string, whose side ports can be both opened and closed by differential and telescopic movement of the main components of the collar in response to rotation of the casing string in a single direction.

This invention has other objects and aspects which will become apparent from a consideration of the embodiment shown in the drawings accompanying and forming part of the present specification. This form will now be described in detail, but it is to be understood that such detailed description is not to be taken in a limited sense, since the scope of the invention is best defined by the claims appended hereto.

Referring to the drawings:

Fig. 1 is a longitudinal view, partly in section and partly in elevation, of an apparatus forming part of a casing string, with its parts in port closing position.

Fig. 2 is a partial longitudinal section of the apparatus, with its parts in port opening position.

Fig. 3 is a view similar to Fig. 2, with the parts in the position to which they have been moved to reclose the ports.

As disclosed in the drawings, a collar apparatus A is connected in a casing string by being attached to upper and lower casing sections B, C. Although specific reference is made in this description to the use of the invention as part of a casing string, it is to be understood that the invention may be installed as a component part of a liner or similar conduit string positioned in a well bore.

The apparatus includes an upper, inner tubular member 10 adapted to be threaded on an upper casing section B, and a lower, outer tubular member 11 adapted to be threaded into a lower casing section C. The upper member 10 is telescoped within the lower member 11, and the two parts are threaded together by means of straight external threads 12 on the inner member engaging companion internal threads 13 on the outer member.

The inner member 10 is provided with a plurality of circumferentially spaced inner side ports 14, and the outer member 11 has a plurality of

corresponding side ports 15 to allow flow of fluid between the interior and exterior of the collar apparatus A. Such flow of fluid, however, can be prevented by an inner sleeve valve member 16 disposed across the inner ports 14, and having a lower head 17 whose lower end 18 is inclined downwardly and inwardly and adapted to engage a companion inclined head or seat 19 at an intermediate portion of the outer member 11 below its ports 15. Assurance is had against passage of fluids through the inner ports 14 by providing a seal ring 20 in an inner circumferential groove 21 in the inner sleeve 16, slidably engaging the exterior of the inner member 10 above its ports 14, and also by a seal ring 22 disposed in the seat 19 of the outer member 11 and engageable with the inclined head end 18 of the inner sleeve. When the sleeve 16 is so disposed over the inner ports 14, fluid is prevented from passing in either direction therethrough.

The inner sleeve 16 is located within an annulus 23 between an upper sleeve extension 11a of the outer member 11 and the inner member 10. This sleeve 16 is secured to the inner member 10 by its straight internal threads 24 engaging companion external threads 25 on the latter. It is to be noted that the external threads 25 extend only part way along the inner member 10, being spaced from the ports 14 and an inner member shoulder 26 defining the end of the annulus 23, and that the companion threads 24 on the inner sleeve 16 extend from its upper end 16a downwardly only part way along its length, in order that the inner sleeve 16 may thread upwardly along the inner member 10 and allow the threads 24, 25 to become disengaged before the upper end 16a of the inner sleeve can abut the shoulder 26 at the upper end of the annulus 23.

Rotation between the inner sleeve 16 and the outer sleeve portion 11a of the outer member is prevented by a suitable spline connection, in the form of a key 27 secured to the outer sleeve 11a, as by means of welding material 28, which key is received within a key-way 29 on the exterior of the inner sleeve 16 in such fashion as to permit relative longitudinal movement between the inner sleeve 16 and outer sleeve 11a.

The threaded connection 12, 13, between the upper and lower members 10, 11 has a lead which is substantially less than the threaded connection 24, 25 between the upper member 10 and inner sleeve 16. Such threaded connections are preferably of the same hand; for example, the threaded connections may be righthand, and the lead of the upper threads 24, 25 connecting the

inner sleeve 16 to the upper member 10 may be twice the lead of the lower threads 12, 13 connecting the upper and lower members 10, 11 together. As a result, rotation of the upper member 10, as to the right, threads it downwardly within the lower member 11 and at the same time effects an upward feeding of the sleeve 16 along the upper and lower members 10, 11.

The collar apparatus A is assembled with the inner member 10 threaded part way into the outer member 11, the sleeve 16 occupying a lower position in substantially full threaded connection with the inner member 10, with its lower portion 17 disposed across the inner ports 14 and its head end 18 in engagement with the seat 19 and seal ring 22 on the outer member 11. As noted above, the upper side seal ring 20 is disposed above the ports 14 to prevent fluid from passing therethrough. The collar, thus assembled, is threadedly attached to the upper and lower casing sections B, C and is run into the well bore as part of the casing string (Fig. 1).

After the casing string has been lowered to the desired depth, circulating fluid may be pumped directly into the casing string and through the collar apparatus A for discharge from the casing string at some point below the collar apparatus, as, for example, from a casing shoe (not shown) at the lower end of the casing string. Following conditioning of the well bore by use of the circulating fluid, a charge of cement slurry may be pumped into the casing string and through the collar (whose inner ports 14 are closed by the inner sleeve 16) for ejection from the shoe at the lower end of the casing string, and for upward passage around the latter toward the collar.

Following setting and hardening of the lower charge of cement slurry, the upper portion of the casing string attached to the collar A may be rotated to the right from the top of the well bore, which also effects rotation of the upper tubular member 10 and threads it downwardly within the outer tubular member 11, whose rotation is prevented by virtue of its attachment to the lower portion of the casing string, which is held stationary by the cement disposed around its exterior. The splined connection 27, 29 also prevents the sleeve 16 from rotating, resulting in threading of the upper member 10 within the sleeve 16. Since both threaded connections 12, 13 and 24, 25 are righthand, rotation of the casing string to the right feeds the inner tubular member 10 downwardly within the outer tubular member 11 and inner sleeve 16. But, since the lead of the upper threads 24, 25 is twice the lead of the lower threads 12, 13, the inner sleeve 16 is moved up along the inner member 10 twice the distance the latter moves down within the outer member 11; that is, the net result is an upward movement of the sleeve 16 along the outer member 11 and the inner member 10.

If the casing string is rotated a predetermined number of turns, the sleeve 16 will be elevated to the position shown in Fig. 2, in which it has moved upwardly to uncover the inner ports 14 and also the outer ports 15, but the upper tubular member 10 has not moved downwardly sufficiently to place the inner ports 14 down below the seat 19 and seal ring 22 of the outer tubular member 11. As a result of such relative movement of the parts, the inner and outer ports 14, 15 are in communication with one another and circulating fluids, followed by a charge of cement slurry, may be pumped directly into

the casing string for outward passage through the open ports and upward flowing through the annulus around the collar A and upper casing string.

Following discharge of the required amount of cement slurry, rotation of the casing string to the right is continued, which continues to feed the upper tubular member 10 downwardly within the lower tubular member 11 and the inner sleeve 16 relatively upwardly along the upper tubular member 10. However, the threads 24, 25 on the inner sleeve and upper tubular member become disengaged to preclude further upward elevational movement of the inner sleeve 16 as a result of rotating the upper tubular member 10. Accordingly, continued downward threading of the upper member 10 within the lower member 11 results in the upper member carrying the inner sleeve 16 with it toward the seat 19 on the lower member, until the head end 18 again engages the seat 19 and seal ring 22 (Fig. 3). The inner ports 14 are then reclosed to prevent passage of fluid between the interior and exterior of the apparatus.

As the tubular string is rotated following engagement of the sleeve head end 18 with its companion seat 19, the shoulder 26 on the upper member engages the upper end 16a of the inner sleeve valve and forces its head end 18 firmly down against the seat 19 to prevent leakage therebetween. The fact of such firm engagement will be transmitted to the operator at the top of the well bore, because of his inability to further rotate the tubing string, since engagement of the shoulder 26 with the upper end 16a of the sleeve and engagement of the sleeve head end 18 with its companion seat 19 preclude further downward threaded movement of the upper member 10 within the lower member 11.

It is to be noted that the inside diameter through the collar apparatus A is no less than the inside diameter through the casing sections B, C, thus providing no restriction to prevent the passage of any devices, such as cementing plugs, completely through the collar. The ports 14 are positively closed initially, and they are positively opened by manipulation of the casing string, which causes the telescopic movement of the upper tubular member 10 within the lower tubular member 11 and a differential movement of the valve sleeve 16 in an upward direction to open the inner ports 14. A continuation of the rotary movement of the casing string in the same direction again effects a positive closing of the ports 14 in leak-proof fashion.

Having thus described my invention, what I claim and desire to secure by Letters Patent is:

1. Apparatus of the character described, including first and second tubular members telescopically arranged with respect to each other, each of said members having means for connecting such member to a casing section, said first member having a side port for allowing fluid flow between the interior and exterior of said first member, a sleeve movable longitudinally along said first member for controlling flow of fluid through said port, means providing a first axial interconnection between said first tubular member and sleeve in order that relative rotation between said first member and sleeve will shift said sleeve along said first member to determine flow of fluid through said port, and means providing a second axial interconnection between said members in order that relative rotation between said members will shift said second member

longitudinally with respect to said first member and its port to determine flow of fluid through said port.

2. Apparatus of the character described, including first and second tubular members telescopically arranged with respect to each other, each of said members having means for connecting such member to a casing section, said first member having a side port for allowing fluid flow between the interior and exterior of said first member, a sleeve movable longitudinally along said first member for controlling flow of fluid through said port, means providing a first axial interconnection between said first tubular member and sleeve in order that relative rotation between said first member and sleeve will shift said sleeve along said first member to determine flow of fluid through said port, means providing a second axial interconnection between said members in order that relative rotation between said members will shift said second member longitudinally with respect to said first member and its port to determine flow of fluid through said port, and means engaging said sleeve to resist its rotation.

3. Apparatus of the character described, including first and second tubular members telescopically arranged with respect to each other, each of said members having means for connecting such member to a casing section, said first member having a side port for allowing fluid flow between the interior and exterior of said first member, a sleeve movable longitudinally along said first member for controlling flow of fluid through said port, means providing a first axial interconnection between said first tubular member and sleeve in order that relative rotation between said first member and sleeve will shift said sleeve along said first member to determine flow of fluid through said port, and means providing a second axial interconnection between said members in order that relative rotation between said members will shift said second member longitudinally with respect to said first member and its port to determine flow of fluid through said port, said first and second axial interconnections being different from each other to produce movement of said sleeve and second member different longitudinal distances with respect to said first member upon relative rotation between said first member and said second member and sleeve.

4. Apparatus of the character described, including first and second tubular members telescopically arranged with respect to each other, each of said members having means for connecting such member to a casing section forming part of a casing string, said first member having a side port, a sleeve movable longitudinally along said first member for controlling flow of fluid through said port, a first threaded connection between said first and second members, a second threaded connection between said first member and sleeve having a different lead from the lead of said first threaded connection, whereby relative rotation between said first member and said second member and sleeve effects relative movement of said sleeve and second member different longitudinal distances along said first member to open and close said port, and means engaging said sleeve to resist its rotation.

5. Apparatus of the character described, including first and second tubular members telescopically arranged with respect to each other, each of said members having means for connect-

ing such member to a casing section forming part of a casing string, said first member having a side port, a sleeve movable longitudinally along said first member for controlling flow of fluid through said port, a first threaded connection between said first and second members, a second threaded connection between said first member and sleeve of the same hand as said first threaded connection but having a different lead from the lead of said first threaded connection, whereby relative rotation between said first member and said second member and sleeve effects relative movement of said sleeve and second member different longitudinal distances along said first member to open and close said port, and means engaging said sleeve to resist its rotation.

6. Apparatus of the character described, including first and second tubular members telescopically arranged with respect to each other, each of said members being adapted for connection to a casing section forming part of a casing string, said first member having a side port, a sleeve on said first member for controlling flow of fluid through said port, means providing a slideable splined connection between said sleeve and second member, a first threaded connection between said first and second members, a second threaded connection between said first member and sleeve having a different lead from the lead of said first threaded connection, whereby relative rotation between said first member and said second member and sleeve effects relative movement of said sleeve and second member different longitudinal distances along said first member to open and close said port.

7. Apparatus of the character described, including first and second tubular members telescopically arranged with respect to each other, each of said members being adapted for connection to a casing section forming part of a casing string, said first member having a side port, a sleeve on said first member for controlling flow of fluid through said port, means providing a slideable splined connection between said sleeve and second member, a first threaded connection between said first and second members, a second threaded connection between said first member and sleeve of the same hand as said first threaded connection but having a different lead from the lead of said first threaded connection, whereby relative rotation between said first member and said second member and sleeve effects relative movement of said sleeve and second member different longitudinal distances along said first member to open and close said port.

8. Apparatus of the character described, including an upper tubular member adapted to be connected to an upper casing section and a lower tubular member adapted to be connected to a lower casing section, said upper and lower members being telescopically arranged with respect to each other and forming part of a casing string, said upper member having a side port, a sleeve on said upper member for controlling flow of fluid through said port and slidably splined to said lower member, a first threaded connection between said upper member and sleeve, a second threaded connection between said upper and lower members of the same hand as said first threaded connection but having a different lead from the lead of said first threaded connection, whereby rotation of said upper member first effects longitudinal movement of said sleeve along said upper member to port opening position and unthreads said sleeve from said upper member,

a continuation of the rotation of said upper member in the same direction then moving said sleeve into engagement with said lower member to close said port.

9. Apparatus of the character described, including first and second tubular members telescopically arranged with respect to each other, said members having a constantly open central longitudinal passage therethrough, each of said members having means for connecting such members to a casing section, said first member having a side port for allowing fluid flow between the interior and exterior of said first member, a sleeve movable longitudinally along said first member to control flow of fluid through said port, means providing a first axial interconnection between one of said tubular members and sleeve in order that relative rotation between said one member and sleeve will shift said sleeve along said first member to determine flow of fluid through said port, and means providing a second axial interconnection between said members in order that relative rotation between said members will shift said second member longitudinally with respect to said first member and its port to determine flow of fluid through said port.

10. Apparatus of the character described, including first and second tubular members telescopically arranged with respect to each other, each of said members having means for connecting such member to a casing section forming part of a casing string, said first member having a side port, a sleeve movable longitudinally along said first member for controlling flow of fluid through said port, a first threaded connection between said first and second members, a second threaded connection between one of said members and sleeve having a different lead from the lead of said first threaded connection, whereby relative rotation between said first and second members and between said one of said members and sleeve effects relative movement of said sleeve and second member different longitudinal distances along said first member to open and close said port, and means engaging said sleeve to resist its rotation.

11. Apparatus of the character described, including first and second tubular members telescopically arranged with respect to each other, each of said members being adapted for connection to a casing section forming part of a casing string, said first member having a side port, a sleeve on said first member for controlling flow of fluid through said port, means for resisting rotation of said sleeve, a first threaded connection between said first and second members, a second threaded connection between said first member and sleeve having a different lead from the lead

of said first threaded connection, in order that relative rotation between said first member and said second member and sleeve effects relative movement of said sleeve and second member different longitudinal distances along said first member to open and close said port.

12. Apparatus of the character described, including first and second tubular members telescopically arranged with respect to each other, each of said members being adapted for connection to a casing section forming part of a casing string, said first member having a side port, a sleeve movable longitudinally along the exterior of said first member for controlling flow of fluid through said port, a first threaded connection between said first and second members, a second threaded connection between said first member and sleeve having a different lead from the lead of said first threaded connection, whereby relative rotation between said first member and said second member and sleeve effects relative movement of said sleeve and second member different longitudinal distances along said first member to open and close said port.

13. Apparatus of the character described, including first and second tubular members telescopically arranged with respect to each other, each of said members being adapted for connection to a casing section forming part of a casing string, said first member having a side port, a sleeve on said first member for controlling flow of fluid through said port, means for resisting rotation of said sleeve, a first threaded connection between said first and second members, a second threaded connection between said first member and sleeve of the same hand as said first threaded connection but having a different lead from the lead of said first threaded connection, whereby relative rotation between said first member and said second member and sleeve effects relative movement of said sleeve and second member different longitudinal distances along said pivot member to open and close said port.
